CLAIM

The ornamental design for a tool handle, as shown and described.

DESCRIPTION

FIG. 1 is a front perspective view of a tool handle according to the present invention;

FIG. 2 is a side view of the tool handle of FIG. 1;

FIG. 3 is a side view, rotated 180 degrees, of the tool handle of FIG. 2;

FIG. 4 is a front perspective view of the tool handle of FIG. 1;

FIG. 5 is a side view of the tool handle of FIG. 1 having a cap detached therefrom; and,

FIG. 6 is a left end view of the cap of the tool handle shown in FIG. 5.
